JEAN B. J. MIGNON AND STANISLAS H. ROUART, OF PARIS, FRANCE.

Letters Patent No. 63,075, dated March 19, 1867.

IMPROVEMENT IN APPARATUS FOR COMPRESSING AIR.

The Schedule referred to in these Letters Patent and making part of the same.

TO WHOM IT MAY CONCERN:

Be it known that we, JEAN BAPTISTE JAVA MIGNON, and STANISLAS HENRI ROUART, of Paris, in the Empire of France, have invented certain new and useful Improvements in Apparatus for Exhausting and Compressing Air, applicable to the transmission of dispatches and other objects through tubes, and to raising water; and we hereby declare the following to be a full, clear, and exact description of the same, reference being had to the accompanying drawings.

The object of our invention is to provide means for producing the exhaustion or compression of air, dispensing at the same time with the employment of machines commonly employed for this purpose; and our invention relates particularly to those machines constructed for the transmission of dispatches or other objects through tubes.

One of the drawings, Figure 1, sheet 1, which accompanies this application, gives a theoretical representation of the principle upon which our invention is based; the details of which, although essentially the same, are in almost every instance varied or modified to adapt it to the particular connection in which it is used.

We will first describe, by reference to the above figure, the general principle which underlies our invention, to which principle we, of course, lay no claim, and will then proceed to indicate, by reference to the other figures, the method and means or apparatus we have devised for practically applying and utilizing this principle to the transmission of dispatches and other objects through tubes.

Our apparatus is based upon the employment of water. Let it be required to effect the exhaustion of air. A reservoir, A, fig. 1, sheet 1, completely closed, is placed underneath other reservoirs which can feed it with water by means of a cock, a. It has a tube, b e, provided with a cock, d, and plunged into an open vessel or reservoir, B, filled with water. The minimum distance which should separate the bottom of the reservoir A from the upper level of the water in the reservoir B is 10m 33. The cock d being closed, the reservoir A is filled with water from the reservoir above by opening the cock a. It is necessary to provide for the escape of the air by a lateral opening or hole which should be carefully stopped or closed after the filling of the reservoir A. When the reservoir A is filled, the cock a is closed and the cock d is opened; the water then flows from the upper reservoir into the lower one, B, and a barometrical vacuum will be formed in a short time in the reservoir A. Let it now be required to compress the air. An open reservoir, C, containing water, is connected with a closed reservoir D, by a plunge-tube, e f, provided with a cock, g. The distance between the two reservoirs may be of any length, as, for instance, the before-mentioned 10m 33. The cock g is opened, and the water flows from the reservoir C into the reservoir D through the plunge-tube e f, and the air contained in the reservoir D is compressed until its tension equilibrates the pressure of the water. With such a difference between the level of the two reservoirs as we have supposed, the air of the reservoir D would have a differential pressure of one atmosphere with the external air. It will be readily understood that the compression produced by means of the water in the reservoir C can be effected as well by a chute leading from a water-course, or by the direct connection of the reservoir D with a pipe or conduit of the water supplied to cities.

In these two operations if the supply of water is exhausted, the same water may be again used by drawing or forcing it up, by means of pumps, into the reservoir where it is needed. Thus, by these two means, we can either exhaust or compress the air. The vacuum obtained is almost perfect, and the compression is as great or as slight as desired, and may be effected upon volumes of air which are limited by nothing except the dimensions of the reservoirs which may be multiplied to any extent, and constructed of masonry and of great size. If it be supposed that we are desirous of availing ourselves of the forces and power which are accumulated on the reservoirs, for the purpose of transmitting dispatches or other objects through a tube, it is clear that we can at pleasure cause the object to approach or to leave us.

The first question, which is of great importance, is the construction of the tubing which should connect the points between which it is necessary to transmit or carry the objects. There are many solutions to this question, but we will here indicate particularly one method which appears to us very practicable for conduits of a certain importance. The tubing is composed of iron pipes constructed of as great length as possible, and as tight, as exact in diameter, as polished on the interior as the most skillful workman can make them. These pipes are united together by means of iron flanchos turned so as to form a male and female joint. Between the flanchos of the joint is placed a gutta-percha disk. In this manner the tubing may be extended to a great

length, care being taken to form as few elbows as possible and to make any change of direction as gradually as the nature of the work will permit.

Whatsoever be the nature of the conduit employed, we propose to place the objects to be transported in carriages, the form of which is shown in Figure 2. These carriages are composed of a box of thin metal. The rear of the box, which approaches a concave form, is provided with a leather, formed of segments, placed fan-like one above the other, as is done in making a pump piston. The front of the box is provided with at least four springs arranged at right angles, and intended to maintain the movement of the carriage parallel to the axis of the tubing.

Such is a general description of the system which we propose to employ, and of which the application comprises some details of a certain importance which we will now proceed to enumerate. We will speak first of the arrangement of cocks, so as to obtain an absolute tightness between the plug of the cock and its seat. To this end the seat is closed at the bottom, and therefore the only passage through which the air can enter or escape is the annular space or circle between the plug and its seat, which is almost infinitesimally small, since the two seats are fitted together with the greatest possible precision and accuracy; and if now a rubber disk be placed over this line or space, and is strongly pressed there, the escape or entrance of the air will be effectually stopped.

This arrangement is shown in Figure 3, in which *a* represents the line of separation between the plug and its seat; *b*, the rubber disk; *c*, a metal disk pressed upon the rubber disk by means of screw-bolts. When these cocks are made of large dimensions, they can be actuated with great ease and facility by means of a worm and wheel.

Figures 4 and 5 represent an arrangement of the organ or device in which the carriages actuated or moved by compression, and especially those carrying dispatches, are received and from which they depart. *A* is a hollow post, which carries on its upper end a hollow pillar, *B*. The end of the conduit or tubing reaches up into the hollow post *A*, and the pillar *B* is connected with the compressed-air reservoir by means of a cock, *R*. The front face of the square part *C'*, fig. 5, of the column *B* is provided with a little door, closed by means of an eccentric-screw, and the lateral faces carry two tubes which connect with the cock *R'* and communicate with the open air. The cocks *R* and *R'* are actuated by the same screw or worm in such manner that their movements shall be contrary, the one being open during the closing of the other. When it is wished to dispatch or send off the carriage, the door is opened and the carriage put in head downwards; the door is then closed and the cock *R* is opened, closing the cock *R'*, and allowing the compressed air to strike against the carriage and to drive it forward. If it be desired to bring back the carriage, the cock *R* is closed, which opens *R'*, allowing the air expelled from the pipe to escape through the lateral tubes *t* and *t'*, and the carriage, continuing its movement, is brought back, being checked and stopped by the cushion of air in the upper part of the column *B*.

In order to remedy certain inconveniences which arise when it becomes necessary to accumulate considerable volumes of air or water, and consequently to have reservoirs of large dimensions, we employ a double-acting machine or apparatus, for compressing the air, composed of two reservoirs *A A'*, Figure 6, divided each into two compartments, *B B' C C'*, by means of a diaphragm, *a b a' b'*. The pipes *c d c' d'*, which conduct the compressing agent, debouch or open at the bottom of the compartments *B B'*. At *e f e' f'* are the tubes for discharging the water, and two plates or slide-valves *g h g' h'* allow of the tubes *c d*, *c' d'*, *e f*, *e' f'* being opened or closed at pleasure. The arrangement of the slide-valves *g h g' h'* is such that when the tube *c d* is closed, *e' d'* and the tube *e f* will be open and the tube *e' f'* closed. The effect of moving the valves is to close the two open pipes and to open those which are closed. The diaphragms *a b a' b'* are each provided with a valve, *K K'*, opening from below. The upper part of the reservoir carries two air-discharge pipes *l l'*, the opening and closing of which are regulated by a thin plate constituting a slide-valve, the movements of which are connected with those of the plates *g h g' h'* in such manner that the orifice *m* will be open when the orifice *e'* is closed, the orifice *m'* closed and the orifice *e* open. At about the height of the diaphragms are balance weight-valves *p p'*, which are actuated by the slightest differential pressure, and whose movements should bear such relation to the waste pipes *l l'* that the valve *p* should be open at the same time with the pipe *l*, and the valve *p'* at the same time with the pipe *l'*.

The operation of the apparatus we have just described is as follows: Let it be supposed that the orifice *c* is open, and, consequently, the orifices *e* and *m*, and the valve *p*, closed. The charge, or compressing water, enters the compartment *B*, compresses the air which it finds therein, lifts the valve *K*, compresses the air in the compartment *C*, and, at the end of a certain time, the air in *C* will be compressed with a determinate pressure. This being accomplished, the system of valves is operated; *m* is opened, and, at the same time with it, *p e* and *C'*, the openings *m' p'* and *E'* being, on the contrary, closed. The water which has accumulated in *B* then flows through *e f*, the compressed air in *C* escapes, or is driven out, to be put to any desired use; and the water flowing into the compartment *B'* through *c' d'* compresses the air in *C'*. The operation of the reservoir *A*, Figure 6, is such as we have just above described, and the action of the reservoir *A'* during the second movement of the valves is similar to that of the reservoir *A* heretofore mentioned. In this manner the air may be exhausted such a number of times within a given space of time as to produce a continuous action or flow.

It now remains for us to indicate the steps to be taken in order to reduce to practice or to utilize the theoretical effects which we have analyzed. These effects may be put to a practical use provided the supply and exhaust orifices of the air and water are opened and closed conformably to the rules we have laid down.

The two cylinders or reservoirs can be placed side by side, as shown in Figure 7. Under this arrangement the entrance of the water into the compartments *B B'*, the discharge of the air of the compartments *C C'*, the discharge of the water from the chambers *B B'*, and the re-entrance of the air into the latter compartments, may be accomplished by means of pipes arranged as shown in the drawings, each pipe being provided with two gates or slide-valves. Thus the water enters through the tube *1* by means of valves *c c'*; the air is exhausted through

the tube 2 by means of the valve $l' l$; the water is discharged through the tube 3 by means of valves $e' e$, and the re-entrance of the air is effected through the tube 4 by means of the valves $p' p$. The four valves, $l' l p' p$, can be arranged in the same plane, and the four valves $l' e' p' e$ are also in a like plane parallel to that of the valves $l' l p' p$.

Figure 8 represents the arrangement of the eight valves, the relative movements of which cause the operation of the machine. The valve e being open, the others should be closed. It is therefore necessary that in drawing the valve e to e' the others should be in the positions $e p l$, and for this purpose it is sufficient to place them on the two arms of the lever $r s, s t$, articulated at $u v$. The valves $e' p' e' l'$ are moved by means of levers $r' s' t'$, articulated at $u' v'$. The line $r s t$ being parallel to the line $r' s' t'$, it will therefore be sufficient to give an oscillating movement to the line $s' s$, or to the middle point of that line, which may be done by means of the water through the intermediary of the sliding differential piston-valve of the single-acting machine. By an analogous arrangement of parts a machine may be made for exhausting the air, composed of two closed reservoirs $A A'$, fig. 9, into which the water enters, and then flows therefrom into an open reservoir placed at a distance of 10m 33 below the reservoirs $A A'$. These reservoirs have a pipe, common to both, for supplying the air, a common inlet through which the water enters, a common outlet for discharging the water, and an escape pipe, common to both, through which the air passes during the filling of the reservoirs. Each of these pipes, like those of the air-compressing apparatus, is provided with two valves. It is necessary that the valves through which the water enters and the air passes out shall be open together; those through which the air re-enters and the water is discharged, being closed; and it is then further necessary that the valve for discharging the water should open and close alone by itself; and, finally, that the air-supply valve should open and then close. This series of movements is all that is needed to operate the apparatus, and may be executed or accomplished by means of valves arranged substantially as hereinbefore described.

It often happens that in operating the apparatus we have described the head of water used to produce compression is greater than is needed for actuating or drawing the carriage in the interior of the tubes. In many cases the power or force may be utilized in order to produce a saving of water; for, let it be supposed that the water which is used has a head or power equivalent to fifteen metres, and that a pressure of five metres will suffice to produce the required movement. Three reservoirs, $A A' A''$, fig. 10, whose united capacity is equal to a volume proportional to the pressure or head of the water, are placed vertically one above the other, the distance between each being five metres. The water is first caused to enter the reservoir A , where it compresses the air which is used to drive the carriage. As soon as this is done the water in A is used to compress the air in A' , and the carriage is thus caused to make a second passage. Then, by conducting the water from A' to A'' , the carriage may be caused to make a third passage, so that the same water will do the same work three times.

It will be understood that the illustration we have just used is only intended for the purpose of giving better and more definite expression to our idea, and that the apparatus may be varied to suit the particular purpose for which it is used. In most instances it will be desired to direct the operation of the different reservoirs to one and the same point, and to this end the reservoirs $A A' A''$ should be made of smaller dimensions, and a reservoir, B , of a capacity proportionate to the size of the others, placed on the ground near them. It should be connected with each one of them, so as to accumulate the compressed air when the others are successively filled with water. If it be desired to produce slighter differential pressures the distance between the reservoirs may be decreased so as to render the action of the apparatus almost continuous. In this case the operation may be made automatic in a very simple manner. Each reservoir should be divided into two compartments, the upper one for receiving the compressed air, the lower one for receiving the water by which the compression is produced. The upper reservoir should have a valve for exhausting the air, which should lift itself at a certain pressure, and a self-closing valve for admitting the air. The lower reservoir should be provided with a valve for discharging the water, which should open of itself when the water has accumulated in sufficient quantity, and a valve for readmitting the air placed laterally in its upper part, and actuated by slight differential pressures.

Having described our invention, what we claim, and desire to secure by Letters Patent, is—

1. The herein-described apparatus for obtaining the compression or exhaustion of air, the same consisting of one or more reservoirs, into and from which the compressing and exhausting agent is conducted so as to compress or exhaust the air within the same by means of supply and exhaust pipes and regulating-valves, arranged and operating substantially as shown and set forth.

2. The combination, with two or more reservoirs, arranged as described, of the air and water-supply and exhaust pipes and their operating valves, connected with the said reservoirs in such manner as to effect the continuous compression or exhaustion of air, substantially as specified.

3. The combination, with one or more air-compressing reservoirs, as described, of a hollow pillar or other tubular receptacle for the dispatches or other objects to be transmitted through the tubing, under the arrangement and for operation as herein set forth.

In testimony whereof they have signed their names to this specification before two subscribing witnesses.

J. MIGNON,
H. ROUART.
